UNITED STATES PATENT OFFICE.

ALBERT E. DIEUDONNE, OF NEW IBERIA, LOUISIANA.

NAME PLATE AND SIGN FRAME.

Application filed July 19, 1926. Serial No. 123,544.

This invention relates to improvements in name plates and sign frames.

One of the main objects of my invention is to provide an improved frame which may be readily stamped from a sheet metal blank, and formed in a manner to provide an attractive display frame for name plates, advertising or other signs and the like.

A further object is to provide a name plate and sign frame which is equally adaptable for different positions of use.

A further object is to provide a frame of the above character which is simple in construction and inexpensive in manufacture.

Other objects will be in part obvious and in part hereinafter pointed out in connection with the accompanying sheet of drawings illustrating two of the various possible embodiments of the present invention, in which

Fig. 1 is a plan of the blank from which the frame is formed.

Fig. 2 is a perspective showing the finished frame.

Fig. 3 is a vertical section of the device as shown in Fig. 2.

Fig. 4 is a view showing an alternative position of the frame in use.

Fig. 5 shows a modification of the device with certain parts broken away.

Referring to the drawings in detail, the numeral 10 designates a sheet metal blank stamped or otherwise cut to the substantial outline shown, and comprising a panel 11, upper and lower depending portions 12 and 13 forming strips, and wing portions 14 and 15. The gripping strips 12 and 13 are formed by bending the depending portions along lines 16 and 17 in a relatively forward direction until a frame structure is formed

by the strips 12 and 13 lying parallel to the panel 11. The bend lines 16 and 17 are spaced to permit insertion of matter of varying depths therebetween. The wing portions 14 and 15 are bent along diagonal lines 18 and the triangular areas 20 and 21 resulting therefrom are brought forwardly forming a base, to lie in a plane at right angles to the panel 11. The main wing portions are then bent backwardly along lines

22 and are likewise maintained in a plane at right angles to the panel 11. The base portions 20 and 21 thus support the panel 11 in an inclined position. Holes 23 for the reception of any desirable fastening means such as nails or screws are provided in the bases 20 and 21.

There is thus provided a frame structure resting of its own weight on the triangular base portions 20 and 21, which form contacting surfaces with the object to which the frame is attached, or upon which the device rests when the frame is used in its horizontal position as shown in Fig. 2. A card name plate or sign 24 of cardboard, paper or the like, is then inserted between the guide strips 12 and 13 and the panel 11 so that its printed matter or pictorial representation is displayed. Superimposed on the card or name plate 24 and similarly held within the guide strips 12 and 13 is a glass or other transparent plate 25. End frames 26 comprising strips of metal bent at right angles along their length are inserted beneath the top and bottom guide strips 12 and 13 to fit snugly over the ends of the name plate and glass surface. It is to be noted that the relatively top and bottom strips 12 and 13 are cut at an angle as at 27 from the panel 11 which is formed substantially longer than the sign or card to be displayed, permitting the angular end portions of the guide strips 12 and 13 to be depressed inwardly to form a lock for the end frames 26. Thus the end frames, glass and card and sign are fitted snugly and securely within the upper and lower strips 12 and 13.

The above described device may be constructed in sizes ranging from a frame to be used with a desk name plate to a frame for displaying a traffic signal and large building signs. In its horizontal position, the frame, as shown in Figure 2, attractively displays advertisements, name plates, and the like, and may be fastened to the surface upon which it rests thru the medium of the fastening holes 23 or may rest on its own weight upon its bases 20 and 21. It is proposed as one of the numerous applications of this device to place the frame on an automobile and positioned below the wind-shield and across the hood saddle of the radiator, as a means of name or residence identification of the owner thereof. In all of its various uses, the inclined or angular positioning of the name plate resting upon the panel 11 furthers easy and quick sighting. In its vertical position, as shown in Figure 4, the device has ready application as a street and traffic sign when attached to a post or a cornice of a house or the like.

In Fig. 5, I have shown a modification

of my invention. An L-shaped back plate 28 corresponding in dimensions to the height and length of the panel 11, is fitted thereto, and welded or soldered along its edges to 5 provide a closed back portion. In this form of the device and in the other embodiments shown, the panel 11 may have a cut-away portion as at 30 if it is desired to illuminate the sign as by means of lamp 31. The 10 closed frame structure shown in Fig. 5 without the illuminating modification is preferably used where a finished appearance of the device is desired.

It is evident that a two-way or combination sign may be provided by placing two of the frames back to back, so that the same or different matter may be seen when the sign is viewed from opposite directions.

Without further analysis, the foregoing 20 will so fully reveal the gist of this invention that others can, by applying current knowledge, readily adapt it for various applications without omitting certain features that from the standpoint of the prior art fairly 25 constitute essential characteristics of the generic or specific aspects of this invention, and, therefore, such adaptations should and are intended to be comprehended within the meaning and range of equivalency of the 30 following claims.

I claim:

1. In a frame for signs or name plates, a sheet metal blank cut to form a panel having a cut-out portion, depending portions 35 bent parallel thereto and spaced therefrom to hold a sign or card between said panel and said depending portions, and wing portions bent to form a base for said panel and to support said panel in inclined position, a member joined to said panel and wing portions, and means positioned between said member and panel to illuminate the sign or name plate.

2. In a frame for signs or name plates, 45 a sheet metal blank cut to form a panel, depending portions bent parallel extending forwardly of said panel and spaced therefrom to hold a sign and a transparent plate

inserted therebetween, removable strips inserted underneath said depending portions 50 to maintain said sign and transparent plate in desired position, and wing portions bent at right angles to said panel and having sections thereof bent along a diagonal to form a base for, and to support, said panel 55 in inclined position.

3. In a frame for sign or name plates, a sheet metal blank cut to form a panel, relatively upper and lower guide strips depending from said panel and spaced from 60 said panel in parallel relation thereto, wing portions extending at right angles to said panel, a portion of said wings being bent along a diagonal in a plane substantially perpendicular to said wing portions to provide a base which supports said panel in inclined position, and an angularly arranged member having a base portion and an upstanding portion, the edges of said 65 portions being joined to the top and bottom edges of said panel and to said wing portions to provide a closed back for said panel.

4. In a frame for signs or name plates, a sheet metal blank cut to form a panel, 75 relatively upper and lower guide strips depending from said panel and parallel thereto and spaced from said panel, wing portions bent at right angles to said panel, a portion of said wings being bent along a 80 diagonal line in a plane perpendicular to said wing portions, a longitudinally disposed L-shaped member joined along its edges to the top and bottom edges of said panel and to said wing portions, a name 85 card or sign positioned on said panel, a transparent plate for said name card or sign, both said name card or sign and said transparent plate being held by said guide strips, said panel having a cut away portion, and means positioned between said panel and said L-shaped member joined thereto to illuminate said card or sign.

Signed at New Iberia, Louisiana, this 12th day of July, 1926.

ALBERT E. DIEUDONNE.
